[57] ABSTRACT

The invention relates to the production of high quality wood chips as a by-product in the manufacture of plywood veneer. The natural outer layer of a log is chipped until the log has a substantially true cylindrical surface whereby an acceptable sheet of veneer can be produced therefrom without waste. The chips produced are suitably for pulp production.

CHIP PRODUCTION AND PLYWOOD VENEER MANUFACTURE

This invention relates to the production of high quality chips as a by-product in the manufacture of plywood veneer.

In the manufacture of plywood veneer, a log of wood is turned against a knife extending across the length of the log. As the log turns and the wood contacts the knife edge, a thin sheet of veneer is peeled off in a long, continuous ribbon of wood. Since the outer surface of the log is not perfectly circular in cross-section, the veneer produced at the beginning of the peeling operation is not uniform in thickness and cannot be used in the manufacture of plywood. Instead, it is usually discarded as waste veneer. This waste veneer is broken up into fragments which are then chipped to produce wood chips for pulping or particle board manufacture. The intermediate breaking operation causes substantial damage to the wood and leads to the production of poor quality chips.

The present invention seeks to eliminate the intermediate step of breaking up the waste veneer and to directly produce good quality wood chips from logs used in the manufacture of plywood veneer.

The invention resides in a method and apparatus for producing good quality wood chips from the waste portion of logs to be used in the manufacture of plywood veneer. To this end, the natural outer layer of a log is directly engaged by a chipping knife assembly to produce such chips. The chipping operation is continued until a substantially true cylindrical surface is formed on the log, when it is discontinued and thereafter a veneer blade applied to the cylindrical surface produces an acceptable sheet of veneer.

The invention will be described with reference to the accompanying drawing, in which

FIG. 1 is an end elevation of an apparatus in accordance with the invention, and

FIG. 2 is a schematic view illustrating the operative steps of the invention.

In the drawing, a log 10 is shown as rotatably mounted, with its axis in horizontal relation, by means of spindles 11 disposed in bearing supports 12 mounted on a base 13. Means, not shown, are provided for rotating the log in the direction of the arrow. The equipment thus far described is conventional in veneer manufacture.

In accordance with the invention, a chipping knife assembly 14 is carried by a holder 15 swingably mounted on a shaft 16 journaled in frame members 17 supported on guides 18. Means for swinging the knife assembly into and out of engagement with log 10 may comprise a lever 19 fixed to shaft 16. Lever 19 is pivotally connected to rod 20 of air cylinder 21 carried by bracket 22 on frame member 17.

Knife assembly 14 preferably comprises a row of uniformly spaced chipping tools 23 seated on the holder 15 and fixed thereto by means of a clamping bar 24. Each tool 23 has a knife edge 25 preferably comprising a major portion 25a of major extent extending in the grainwise direction of the log and end portions 25b of minor extent extending angularly with respect to portion 25a. It will be apparent that when the knife assembly is swung into engagement with the log surface, the knife edges 25 will initially engage the log surface to produce chips 26 and to form grooves in the log surface with intervening land areas.

Guides 18 are mounted for sliding movement on complementary guide members 27 fixed to a main base 28.

Also releasably fixed to guides 18, as by means of a latch 29 and latch lever 30, is a veneer blade linkage 31 to which is fixed a veneer blade holder 32. A veneer blade 33 is fixedly seated in the holder as by means of a clamping plate 34. As shown, blade 33 is vertically disposed whereby its cutting edge 33a may engage the log in perpendicular relation to the plane of the horizontal axis of the log. It will be observed that the blade 33 engages the log at a level lower than the level of engagement of the chipping knives.

Means for adjustably moving the entire blade assembly as carried by the guides 18 in a direction towards and away from the log comprises a wheel 35 fixed to shaft 36, bevel gear 37 on shaft 36, meshing bevel gear 38 on lead screw 39 mounted in bearing 40, a split nut 41 fixed to guide 18 and through which the screw 39 is threadedly received, and a nut release 42.

It will be apparent that certain parts of the device will be duplicated on the other side of the machine (not shown) including guide 18, guide member 27, frame member 17, lever 19, air cylinder 21, latch 29, latch lever 30, bevel gears 37, 38 and lead screw 39.

In operation, a log is placed in the operative position described, such log having thereon its outer natural layer 43 the surface of which is normally of highly uneven character.

With the log rotating and the chipping knife assembly 14 and veneer blade 33 moved into suitably adjusted engagement therewith by means of the wheel 35, the chipping tools 23 produce the chips 26 and directly thereafter the blade 33 produces chips 44 by removal of the land areas resulting from the chipping operation of tools 23. It will be apparent that the depth of cut of the tools 23 and of the blade 33 will be equal so that eventually a true cylindrical surface will be formed on the log. At that time the cylinders 21 are actuated to swing the knife assembly 14 out of engagement with the log and thereafter an acceptable veneer sheet containing no waste sections will be produced by the blade 33.

The knife assembly 14 is preferably of the type described in Canadian Pat. No. 676,095, which by reason of the knife edge configuration and application produces chips of such characteristics that they may be employed for the production of high quality pulp.

In any event, the chips produced are directly usable for pulp or particle board manufacture without intermediate processing. Thus, more effective and efficient use of the waste product of veneer manufacture is achieved.

I claim:

1. In the manufacture of plywood veneer, a method of producing wood chips from the waste portion of logs which comprises rotating said log about its axis, chipping the natural outer layer of said log to produce a plurality of chips of a predetermined size range suitable for pulping, said chipping step including the steps of applying an aligned row of chipping tools to said natural outer layer of said rotating log to produce a plurality of chips and to form a series of grooves with intervening land portions in said layer, applying a veneer blade to said layer to remove said land portions and to produce chips therefrom, continuing said application of chipping tools and veneer blade until said natural outer

layer has been removed and said log has a substantially true cylindrical surface and then withdrawing said chipping tools from said log and engaging said cylindrical surface with said veneer blade to produce a sheet of veneer of substantially uniform thickness throughout its extent.

2. A method of producing wood chips as defined in

claim 1, including the step of rotating said log about its axis, and wherein said chipping step includes the step of applying a cutting edge of each of said grooving tools to said log in a direction parallel to the grain of the log and at least one other cutting edge of said tool to said log in a direction angularly of the grain of said log.
